UNITED STATES PATENT OFFICE

126,721

DESIGN FOR A STRAIN INSULATOR

Lorell John Schilling, Brookfield, Ill., assignor to
Babson Bros. Co., a corporation of Illinois

Application August 2, 1940, Serial No. 94,134

Term of patent 14 years

To all whom it may concern:

Be it known that I, Lorell John Schilling, a citizen of the United States, residing at Brookfield, in the county of Cook and State of Illinois, have invented a new, original, and ornamental Design for a Strain Insulator, of which the following is a specification, reference being had to the accompanying drawing, forming a part thereof, in which:

Figure 1 is a top plan view of a strain insulator, showing my new design; Figure 2 is a side elevational view of the insulator shown in Figure 1; and Figure 3 is a bottom plan view of the same insulator.

I claim:

The ornamental design for a strain insulator, as shown.

LORELL JOHN SCHILLING.
